UNITED STATES PATENT OFFICE.

MARTIN LEBEIS, OF BERLIN-FRIEDENAU, GERMANY, ASSIGNOR, BY MESNE ASSIGNMENTS, TO REMINGTON RAND INC., OF NEW YORK, N. Y., A CORPORATION OF DELAWARE.

PUNCHING MACHINE FOR STATISTICAL CARDS.

Application filed June 30, 1925, Serial No. 40,624, and in Germany July 3, 1924.

This invention relates to a punching machine for statistical or filing cards of that kind in which all the punches are first set and then all the holes are punched simultaneously. Two kinds of punching machines are at present known. In one of them the punches are singly and consecutively set by means of a keyboard with ten keys, by means of a setting mechanism advancing step by step like the carriage of a typewriter and connected to the keyboard. In the second kind, slides are provided to the same number as that of the rows of punches, or a full keyboard. The slides form, so to speak, a large keyboard with all the numbers thereon.

The first construction presents the disadvantage that the operator cannot observe the setting, so that errors are easily liable to occur. In the second construction, the disadvantage is the large space occupied by the setting board, and the consequent difficulty to observe at a glance what has been set, as well as the complication of setting by pulling the slides.

The disadvantages of both constructions are eliminated by my invention. This invention substantially consists in a limited size keyboard with all the numbers thereon, for instance of nine places, being mounted adjustably directly above the punch boxes which are stationary as in the known constructions, and moved by means of a separately arranged tabulator after a group of figures has been set. The full keyboard follows the card diagram to be treated therefore in columns. As the keys are held fast until the next movement of the carriage, the operator always has before him the group of figures set, and can control or check it separately, which is easier than if he had to check at once the whole number of figures.

A construction according to the invention is illustrated by way of example in the accompanying drawings in which

Figure 1 is a vertical section at right angles to the longitudinal direction of the machine.

Figure 1^a is a detail view of the key locking means of the same.

Figure 2 shows on an enlarged scale a part of the punch box with the setting device.

Figure 3 is a vertical longitudinal section. 55
Figure 4 is a partial plan of the machine.
Figure 5 shows the feeding device.

The punch box with the perforators or punches and the matrix is of the construction usual in card punching machines. 60

Between two plates 1 and 2 (Figures 1 and 2) secured to the frame of the machine, are arranged the punches 3. Under the punches is arranged the hole plate or matrix 4 which can be raised by a pair of eccentrics 65 6 mounted on the spindle 5, by means of rollers 7. A perforation or punching of the card K placed on the matrix is then effected at those points at which the punches are locked in the low position shown in Figure 70 2 for the central punch. This locking is effected by means of pawls 8 which are adjustably mounted between the guide plates 16 and 17 also secured to the frame of the machine, and may be depressed by the keys 75 9 and held fast in the low position by locking slides 9.

The setting carriage comprises an upper plate 10 and a lower plate 11 which are connected together to form a fixed frame 80 by means of lateral sheet metal plates 12 (Figure 3). This frame is easily adjustable in the lateral direction on rails 13 and 14 which are secured to the machine frame, and is pulled to the right by means of two 85 steel bands 15 (Figure 4) by a spring mechanism not shown in the drawing. The pawls 8 are set directly by means of the keys. As the keys must be arranged so as to ensure convenient striking, and as the arrangement of the pawls depends on the fixed arrangement of the holes in the card, the transmission parts between the keys and the pawls must be brought together in a correspondingly narrow space. This can be 95 done either directly by using bent key levers or, as shown in the drawings, by pushing parts which may be in the form of Bowden wires (Figure 1). It will be seen that the Bowden wires are grouped in a 100 conical or converging arrangement (see Figs. 1 and 3). In this case, to the upper plate 10 and to the lower plate 11 are carried closely wound spirals or helical springs 18 (Figure 1^a) inside each of which is arranged 105 a thin wire 32 which constitutes the transmission element. To the wires 32 are connected the key stems 21 carrying the keys

20. A pressure spring 37 arranged inside the socket for the spiral keeps the keys in the normal position. When a key is depressed, the corresponding pawl 8 (Figure 2) is therefore depressed, the slide 9 snaps into the upper recess of the pawl and holds it fast, and the punch 3 is held in its lower position in opposition to the action of its spring. In the case of a keyboard with 10 nine places, punches may be set accordingly in nine rows.

In order to enable the whole range of the punching box to be set with the keyboard, the latter, as already stated, is adjustable 15 in the lateral direction. Under the action of pulling by the bands 15 operated by a tension spring, the whole keyboard has the tendency to move to the right, but is prevented from doing so by the finger 28 which 20 engages in front of one of the stops 23 (Figures 1, 3 and 5). The stops are mounted in slots in a rack 24 secured to the frame of the machine. The stops may be placed at 25 any desired points of the said rack. The release of the setting carriage is effected by 30 a separate key 25 which acts on a lever 22. This lever rests on an arm 26 having a wide hub 27 with a tappet 28, which is so mounted on the spindle 29, that, under the action of a spring 30, it moves to the right on the 35 said spindle. Moreover the tappet is so connected to the spindle by a groove and spline that the spindle participates in the rotation of the lever. To the spindle is also secured a second tappet 31. The two tappets 28 and 31 are so arranged at an angle to each other so that in the two end positions of the oscillation, one of them engages with one of the 40 stops 23. The parts 25 to 31 and 38 are secured to the setting carriage. If the key 25 is depressed, the tappet 28 is turned by means of an intermediate lever 22 and the arm 26 so that it is released from the stop 23 in front of which it had been situated, 45 and moved to the right by the action of the spring 30. At the same time, the tappet 31 has assumed the position which was previously occupied by the tappet 28, but as it is in front of the stop 23 with which the 50 tappet 28 was previously in engagement, the carriage is free and is moved also to the right by the action of the pulling bands 15, until the tappet 31 is stopped by the next stop 23. If the key 25 is now released, the 55 tappet 31 will be released from the stop 23, the carriage is moved a little further still to the right, until the tappet 28 which has by now returned to the position of rest, strikes the stop 23, and its spring 30 is compressed 60 until the lever 26 strikes the stop pin 38. In that way the setting carriage reaches its new position. The spring 30 forms at the same time an elastic buffer for absorbing any shocks produced by the carriage. When 65 the setting of the keys has been effected in

this position, the key 25 is again depressed, the carriage moves to the next stop and so on. In that way it is therefore possible to set the whole punching box by means of the small keyboard.

In order to render possible a checking of the figures set, the keys depressed in one position of the carriage, may be locked in this position for the whole period of this adjustment. This is done in the following 75 manner:

The wires 32 (Figure 1^a) terminate in locking cones 35. These cones are held fast by a locking bar 36, of which there is one for 80 each row of keys, as soon as they are depressed down to the neck. The key remains therefore in the depressed position, and the figures set may be read on the keys thus locked. The advance key 25 releases the locking bars, that is to say, makes them 85 free for a new adjustment at each advance of the carriage.

What I claim is:—

1. In a punching machine for statistical cards, a punching device having a plurality 90 of rows of punches, corresponding rows of punch locking devices, a movable setting carriage having a keyboard provided with several rows of keys and provided with corresponding rows of key operated devices 95 adapted to set in operative position punch locking devices above a plurality of punch rows which form a zone or portion of the total number of punch rows, a card carrier movable relatively to the locked punches, tabulating means including a tabulating key for moving said setting carriage step by step from zone to zone of the rows of punches, and means cooperating with the inner ends 100 of said key operated devices to lock the keys in depressed position, said key locking devices being releasable by depression of the tabulating key.

2. In a punching machine for statistical cards, a punching device comprising a plurality 110 of rows of punches, corresponding rows of punch locking devices, a movable setting carriage provided with a keyboard having several rows of keys and having corresponding rows of key operated setting devices adapted for each position of the carriage to set in operative position punch-locking devices in all of the rows in a corresponding zone, a card carrier movable relatively to the locked punches, said setting carriage being movable step by step from zone to zone of the punches corresponding to zones on the rows of punches, connections between said keys and said key locking devices 115 having at their inner ends conical members for operating the punch locking devices and locking the keys in depressed position.

3. In a punching machine for statistical cards, a punching device comprising a plurality 120 of punches providing a plurality of

zones each containing a plurality of rows of punches, a movable setting carriage having a keyboard provided with several rows of keys and provided with corresponding rows of key operated punch locking devices adapted for each position of the carriage to lock punches in operative position in all the rows in a zone, a card carrier movable relatively to the locked punches, said setting carriage being movable step by step from zone to zone of the punches, and Bowden wires actuatable by said keys to set said punch-locking devices and provided at their inner ends with means for locking the actuated keys in depressed position.

4. In a punching machine for statistical cards, a punching device comprising a plurality of rows of punches, corresponding rows of punch locking devices providing zones corresponding to zones on a card and including for each zone a plurality of rows of punches and corresponding rows of punch locking devices, a movable setting carriage having a keyboard provided with several rows of keys corresponding to the number 25 of rows of punches in a zone and corresponding rows of key operated devices for operating said punch locking devices, said punch locking devices including locking bars within the setting carriage, a card carrier movable relatively to the locked punches, means for moving said setting carriage step by step from zone to zone of the punches and of the card to be punched, and connections between the said keys and said punch locking devices on the setting carriage said connections including convergently arranged Bowden wires having locking cones on their inner ends for locking the actuated keys in depressed position. 40

In testimony whereof I have signed my name to this specification.

MARTIN LEBEIS.
